UNITED STATES PATENT OFFICE.

HOWELL W. WRIGHT, OF NEW YORK, ASSIGNOR TO ANNA J. BROWNELL,
OF BROOKLYN, N. Y.

LAMP.

SPECIFICATION forming part of Letters Patent No. 271,181, dated January 23, 1883.

Application filed July 11, 1882. (No model.)

To all whom it may concern:

Be it known that I, HOWELL W. WRIGHT, of New York, in the county of New York and State of New York, have invented a certain 5 new and useful Improvement in Lamps, of which the following is a specification.

The object of my improvement is to provide a simple means for fastening together the parts of metal and glass or ceramic ware 10 which are so commonly employed in the construction of lamps, especially those of the more ornate styles. Heretofore such parts have commonly been secured together by plaster-of-paris. This becomes saturated with oil 15 or deteriorates from other causes and releases the parts. Moreover, much labor is involved in fastening the parts together by the use of this material. In many cases it is desirable to so fasten the parts that they may conveniently be detached and reattached, and to do so is impossible when they are fastened by plaster-of-paris.

My improvement consists in providing the glass or ceramic parts and the metal parts 25 with corresponding rims having their meeting surfaces made in the form of annular wedges, so that they may be fitted together and turned to clamp and securely fasten them.

In the accompanying drawings, Figure 1 is 30 a sectional side view of a lamp-stand embodying my improvement. Fig. 2 is a horizontal section, on a larger scale, taken through the body and collar of the same. Fig. 3 is an inverted plan of the collar. Fig. 4 is a plan of 35 the body. Fig. 5 is an inverted plan of the body. Fig. 6 is a plan of the pediment or base-piece, and Fig. 7 is a vertical section of the upper part of a lamp-reservoir and a burner affixed thereto.

40 Similar letters of reference designate corresponding parts in all the figures.

A designates the base-piece of the lamp-stand. It is made of metal, preferably such a metal as Britannia metal, and has its exterior embellished in any desirable manner. At the top it is provided with a rim, a.

B designates the body of the lamp-stand. It is made of glass or of any suitable kind of ceramic ware, and is provided at the lower

end with a peg, b. The rim or exterior of the 50 peg b and the interior of the rim a of the base-piece are made in the form of annular wedges, so that when the peg is fitted into the rim of the base-piece and turned slightly around the two will become firmly wedged and clamped 55 together. They will have a continuous bearing. Hence they will be securely fastened; but whenever it is desired they may be separated by turning them in the reverse direction and pulling or lifting one from the other. At the 50 upper end the body has a rim, c.

C designates a collar, which may be made of the same kind of metal as the base-piece of the lamp-stand. It is adapted to surround the rim c of the body and to lap over the upper edge thereof. The exterior of the rim c of the body and the interior of the rim of the collar are made in the form of annular wedges. When fitted together and turned they are securely clamped together. By turning them 70 reversely they may be disengaged and separated.

By my improvement I provide a very simple means for fastening together parts of metal and glass or ceramic ware used in the 75 construction of lamp-stands. It saves the plaster-of-paris commonly employed to fasten such parts together, and also reduces the cost by saving the labor involved in the use of plaster-of-paris. After the parts are fastened 80 together by my improvement they may be readily detached, even by persons having little or no mechanical skill. This is advantageous, because the parts may be cleaned more easily when separate. Moreover, the 85 metal parts can be scoured vigorously without any danger of damaging the parts made of glass or ceramic ware.

Other parts of a lamp may be united in the same manner as the parts described.

Although I have only described my improvement in connection with a lamp-stand, it obviously may be used in a variety of articles of similar or analogous construction. In Fig. 7 I have shown a collar, C, fitted to an oil-reservoir, 95 and a lamp-burner, D, fitted to the said collar, according to my improvement. This attachment is especially advantageous for a lamp-

burner, as it provides for attaching and detaching the same quickly and far more easily than when a screw-thread is employed. The collar C here shown may be stamped up in 5 dies.

What I claim as my invention, and desire to secure by Letters Patent, is—

In a lamp-stand or other like article composed of a part or parts of metal and a part

or parts of glass or ceramic ware, the combination of rims on the said parts, having their meeting surfaces made to form annular wedges, substantially as and for the purpose specified.

HOWELL W. WRIGHT.
